CLAIM

The ornamental design for an ice cube tray, as shown and described.

DESCRIPTION

FIG. 1 is a top, front and side perspective view of an ice cube tray showing our new design;

FIG. 2 is an exploded perspective view of the components thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof;

FIG. 9 is a cross-sectional view taken on line 9—9 in FIG. 3; and,

FIG. 10 is a cross-section view taken on line 10—10 of FIG. 3.

FIG. 1

FIG. 2

FIG. 5

FIG. 6

FIG. 7

FIG. 8

FIG. 10
